A. A. YERKES.

MANIFOLDING SALES BOOK.

APPLICATION FILED APR. 19, 1917.

1,291,340.

Patented Jan. 14, 1919.

UNITED STATES PATENT OFFICE.

ADOLPH A. YERKES, OF ELMIRA, NEW YORK, ASSIGNOR TO AMERICAN SALES BOOK COMPANY, LIMITED, OF TORONTO, ONTARIO, CANADA, A CORPORATION OF ONTARIO.

MANIFOLDING SALES-BOOK.

1,291,340.

Specification of Letters Patent. Patented Jan. 14, 1919.

Application filed April 19, 1917. Serial No. 163,123.

To all whom it may concern:

Be it known that I, ADOLPH A. YERKES, a citizen of the United States, residing at Elmira, in the county of Chemung and State 5 of New York, have invented certain new and useful Improvements in Manifolding Sales-Books, of which the following is a full, clear, and exact description, such as will enable others skilled in the art to which 10 it appertains to make and use the same.

This invention relates to manifolding devices, and with regard to its more specific features, to manifolding salesbooks.

An object of this invention is to enable a 15 multiple record to be made in a practical manner.

A further object of this invention is to enable a multiple record to be made in such a manner that one of the records may be 20 allowed to remain in the book without interfering with the subsequent operation of the book.

A further object is to provide a practical book of the character described in which 25 three of the records will be direct reading.

Other objects will be in part obvious and in part pointed out hereinafter.

The invention accordingly consists in the features of construction, combinations of 30 elements and arrangement of parts which will be exemplified in the construction hereinafter set forth, and the scope of the application of which will be indicated in the following claim.

35 In the accompanying drawings forming part of this specification and wherein similar reference characters refer to similar parts throughout the several views,—

Figure 1 is a perspective view of a book 40 embodying this invention; and

Fig. 2 is a side view showing the leaf arrangement.

The numeral 1 designates a pad comprising a plurality of sheets bound together by 45 staples 2, each of said sheets being folded upon itself in a zigzag manner to form three superposed leaves 3, 4 and 5. Operatively associated with the leaves 3, 4 and 5 and in position to be interposed between leaves 4 50 and 5, is a transfer leaf 6 which is conveniently bound integral with the pad. This transfer sheet may be notched, as shown at 6^a, to permit the ready removal of the leaves 3 and 4 from beneath it. Suitable transfer 55 material is also placed between the leaves 3

and 4 to provide the record upon the leaf 4. This transfer material may be conveniently provided by carbonizing the under surface of the leaf 3, which leaf, it will be observed, is the top leaf of the superposed leaves and 60 is the end leaf of the folded sheet.

Also bound integral with the pad 1 is a support 7 extending substantially the length of the pad, and attached to the support 7 and extending parallel therewith is a back 8 65 which is sufficiently long to project beyond the bound edge of the pad 1, thus forming a pocket between the support 7 and back 8. In order to make this pocket as long as possible, the support 7 may be attached to 70 the rear of the back 8 and may be folded over its ends, as shown, or the parts 7 and 8 could be made integral. Attached to the projecting end of the back 8, as by staples 9, is a second pad 10, of preferably transparent leaves. By this construction it will be evident that the sheets of the pad 9 may be placed over or between the leaves of the pad 1 or between the support 7 and the back 8. 80

In order conveniently to hold the book there may be provided a cover 11 comprising a back portion 12 and a front portion 13 hinged together, as at 14. Projecting from the back portion 12 is a flange 15, and pivoted to the lower end of the flange 15 is a bail 16. Attached to the back of the pad 1, as by being bound by the staples 9, is a flap portion 17. The flap portion 17 is adapted to be slipped through the bail 16, and the bail 16 is of such length as to permit the pad 10 to be pushed down beside the flange 15, as shown. Pivoted also to the end of the back portion 12 is a U-shaped member 18, to the outer end of which is pivotally 85 mounted a separator 19, preferably of metal. The U-shaped member 18 is of such length and so disposed that the separator 19 may be folded out of the way to permit access to the sheets, or may be inserted between 100 consecutive sets of sheets.

In the insertion of the pad in the book the bail 16 may be folded upwardly from the back 12 and the flap 17 inserted therethrough. The pad and bail may then be 105 pressed downwardly toward the back portion 12 until the end of the pad is beside the flange 15, in which position the flange will keep the pad from slipping out of engagement with the bail.

The carbon sheet 6 will normally overlie the record sheets of the pad 1, and the pad 10 will normally overlie the pad 1. In the manipulation of the book the leaves of the pad 10 are first thrown back to expose the pad 1. The upper end of the leaves 3 and 4 may then be grasped through the notch 6^a and removed from beneath the carbon sheet, allowing the carbon to fall on the leaf 5. 5
10 The rear sheet from the pad 10 may then be laid over the carbon and the leaves 3 and 4 folded back in place. Any record which is made upon the sheet 3 will thus be transferred to the leaf 4 by the carbon material on the rear face of the leaf 3, to be transferred to the rear side of the sheet from the pad 10 by the upper face of the sheet of transfer material, and will be transferred to the leaf 5 by the under face of 15
20 the sheet of transfer material. The leaves 3, 4 and 5 may now be torn from the book and the pad 1 and support 7 may be lifted to enable the sheet from the pad 10 on which the record has just been made to be placed 25 between the support 7 and back 8. The upper corner of the leaves 3 and 4 from the next sheet of the pad 1 may then be grasped through the notch 6^a in the transfer sheet and lifted over the carbon sheet, whereupon 30 another sheet from the pad 10 may be placed over the carbon and the leaves 3 and 4 again put in place, making the book ready for a new record.

Thus by the above described construction 35 are accomplished, among others, the objects hereinbefore referred to.

As many changes could be made in the above construction and many apparently widely different embodiments of this invention could be made without departing from 40

the scope thereof, it is intended that all matter contained in the above description or shown in the accompanying drawings shall be interpreted as illustrative and not in a limiting sense. 45

It is also to be understood that the language used in the following claim is intended to cover all of the generic and specific features of the invention herein described and all statements of the scope of 50 the invention, which, as a matter of language, might be said to fall therebetween.

Having described my invention, what I claim as new and desire to secure by Letters Patent is: 55

A manifolding device comprising, in combination, a pair of pads, a back to which each pad is secured, one of said pads being secured to said back by a pad support flexibly connected to said back at the end opposite the bound end of the leaves of the last mentioned pad, the other pad being secured to the back so that the leaves thereof are adapted to underlie and overlie the other pad, the pad which is connected to said back by said support comprising sheets each folded upon itself to form three superposed leaves, the top leaf of each sheet being the end leaf thereof and being coated with transfer material on its under face, and a double 60 face carbon sheet carried by the back and adapted to lie against the upper face of the lowest leaf of said folded sheet. 65

In testimony whereof I affix my signature in the presence of two witnesses. 70

ADOLPH A. YERKES.
